UNITED STATES PATENT OFFICE.

CHARLES G. EDWARDS, OF RUSHFORD, MINNESOTA.

DOOR-ALARM.

SPECIFICATION forming part of Letters Patent No. 339,750, dated April 13, 1886.

Application filed December 16, 1885. Serial No. 185,793. (No model.)

To all whom it may concern:

Be it known that I, CHARLES G. EDWARDS, a citizen of the United States, residing at Rushford, in the county of Fillmore and State 5 of Minnesota, have invented certain new and useful Improvements in Alarm Attachments to Doors; and I do hereby declare that the following is a full, clear, and exact description of the same, reference being had to the annexed 10 drawings, making a part of this specification, and to the letters and figures of reference marked thereon.

Figure 1 of the drawings is a front elevation of a portion of a door and door-frame, 15 showing my invention applied thereto; Fig. 2, an edge view, on an enlarged scale, of the striking mechanism; and Fig. 3, a detail plan view of the bracket, showing the spring-connection.

20 The present invention has relation to that class of alarm attachments to doors in which is employed a bell connected by a bracket to the door-frame, and a hammer pivoted to said bracket, an arm upon the door operating the 25 hammer to sound the bell when the door is being opened.

The object of the invention is to improve the construction of the above-mentioned class 30 of alarm attachments; and it therefore consists in the details of construction, substantially as shown in the drawings, and hereinafter described and claimed.

In the accompanying drawings, A B represent, respectively, the door and door-frame, 35 to the former of which is attached an arm, *a*, said arm projecting above the door to operate the striking mechanism of the bell C, the bell being connected in any well-known manner to the door-frame.

40 The striking mechanism consists in part of a bracket, D, of any preferred construction, which is secured to the door-frame B, and is provided with ears *b*. To the ears *b* are pivoted similar ears, *c*, of a lever, E, the rod or 45 pin *d*, which connects the ears together, having coiled around it a spiral spring, F, the extremities *e f* thereof bearing, respectively, upon the sides of the bracket D and lever E, as shown in Fig. 2.

50 The lever E at one end is bent inwardly toward the bracket to form a stop, *i*, and there- by limiting the throw of the hammer *g* when

the lever is released by the arm *a*. This hammer *g* is secured to the free end of a curved rod, G, the opposite end thereof being firmly 55 attached to the end of the lever E, or near the end, as found desirable. The rod G, as will be noticed, has a serpentine form to increase its efficiency and bring the hammer *g* in proper position to the bell. 60

The bracket D, on which is supported the lever E, may be constructed in any desirable manner and provided with holes for the screws, which secure the bracket to the door-frame in a suitable position to have the hammer 65 strike the bell when the door is opened.

When the door is closed, the end of the rod or arm *a* bears with sufficient force against the outer end of the lever E to hold the hammer *g* from contact with the bell C; but when 70 the door is opened sufficiently to withdraw the arm from contact with the lever, the latter, by the action of the spring F, will be thrown out to bring the hammer against the bell with the required force to sound an alarm. When 75 the door is again closed, the rod or arm *a*, which is brought against the lever, will cause the hammer *g* to be held from contact with the bell, and thus prevent sounding an alarm when the door is closed. 80

Having now fully described my invention, what I claim as new, and desire to secure by Letters Patent, is—

In an alarm attachment to doors, the combination, with a bell and an upwardly-extending arm connected, respectively, to the door-frame and door, of a striking mechanism consisting of a bracket formed with ears, a lever having ears pivoted to the ears of the bracket, a spring coiled around the pivot and 85 having its ends bearing on the inner sides of the bracket and lever, said lever bent inwardly at its ends, as shown, and having attached to it a serpentine-formed rod carrying 90 the hammer, substantially as and for the purpose set forth. 95

In testimony that I claim the above I have hereunto subscribed my name in the presence of two witnesses.

CHARLES G. EDWARDS.
